INVENTOR.

Frederick Dietrich
BY
John O. Brady
ATTORNEY

UNITED STATES PATENT OFFICE.

FREDERICK DIETRICH, OF NEW YORK, N. Y., ASSIGNOR TO BRANDES LABORATORIES, INC., OF NEWARK, NEW JERSEY, A CORPORATION OF NEW JERSEY.

DESIGN FOR A LOUD SPEAKER.

Application filed June 28, 1926. Serial No. 18,198. Term of patent 14 years.

To all whom it may concern:

Be it known that I, FREDERICK DIETRICH, a citizen of the United States of America, residing in New York, in the county and State of New York, have invented a new, original, and ornamental Design for a Loud Speaker, of which the following is a specification, reference being had to the accompanying drawing, forming part thereof.

Figure 1 is a front view showing my new design; and Fig. 2 is a side view showing my design of loud speaker.

I claim:

The ornamental design for a loud speaker as shown.

FREDERICK DIETRICH.
